PRESSURE FLUID MOTOR

Mervin Chester Huffman, Claremont, N. H., assignor to Sullivan Machinery Company, a corporation of Massachusetts

Application September 12, 1932, Serial No. 632,728

11 Claims. (Cl. 121—19)

This invention relates to pressure fluid motors and more particularly to improvements in the fluid distribution means of a pressure fluid motor of the type particularly adapted to use in hammer rock drills.

An object of this invention is to provide an improved pressure fluid motor. Another object is to provide improved fluid distribution means for a pressure fluid motor. A further object is to provide an improved pressure fluid motor of the hammer type particularly adapted to use in rock drills. A further object is to provide in a motor of the above character an improved valve mechanism for controlling the supply of pressure fluid to the piston chamber in an improved manner. These and other objects of the invention will, however, hereinafter more fully appear in the course of the following description and as more particularly pointed out in the appended claims.

In the accompanying drawings there is shown for purposes of illustration one form and a modification thereof which the invention may assume in practice.

25 In these drawings,—

Fig. 1 is a central, longitudinally extending, vertical sectional view of the preferred illustrative embodiment of the invention.

Fig. 2 is a view similar to Fig. 1 showing the fluid distributing valve and motor piston in a different position.

Fig. 3 is a front end elevational view of one of the valve chest elements per se.

Fig. 4 is an elevational view of the fluid distributing valve per se.

Fig. 5 is a view similar to Fig. 1 showing the parts in a hole blowing position.

Fig. 6 is a transverse vertical sectional view taken substantially on line 6—6 of Figs. 1 and 5.

40 Fig. 7 is a fragmentary horizontal sectional view taken substantially on line 7—7 of Fig. 6.

Fig. 8 is a detail sectional view taken substantially on line 8—8 of Fig. 6.

Fig. 9 is an enlarged detail sectional view showing the distributing valve and its associated passage means.

Fig. 10 is a fragmentary view similar to Fig. 5 showing a modified form of construction.

In this illustrative embodiment of the invention there is shown a pressure fluid motor of the hammer type particularly adapted to use in rock drills comprising a motor cylinder 1 having a piston chamber 2 containing a reciprocable hammer piston 3. The hammer piston is provided with an integral cylindrical extension or

striking bar 4 projecting forwardly through a bushing 5 carried within a front buffer ring 6 herein forming the front head of the motor. Rotatably mounted within a chuck housing 7, as clearly shown in Fig. 5, is a chuck sleeve 8 carrying a chuck bushing 9. Supported within the chuck bushing is the shank 10 of a usual hollow drill steel, the shank 10 projecting rearwardly within a chamber 11 formed in the chuck sleeve in a position to receive the impact blows of the piston striking bar 4 in the manner well understood in the art. Secured to the cylinder 1 at the rear end thereof is a back head 12, and this back head and the front head 6, the chuck housing 7 and the cylinder are held in assembled relation by any suitable means, herein by usual side rods 13, 13, as shown in Fig. 6. As is usual in rock drilling tools, the drill steel is rotated by the hammer piston as it is percussively actuated thereby, and this rotation means consists of a usual ratchet and pawl device 14 including a stationary ratchet ring 15 and an oscillatory pawl carrier 16, herein formed integral with a rifle bar 17 herein arranged at the rear end of the motor cylinder in axial alignment therewith and extending forwardly within the piston in engagement with a rifle nut 18 secured within the piston, as shown in Fig. 1. As the motor piston moves forwardly, the pawls of the pawl carrier slip over the ratchet teeth, thereby permitting an unimpeded forward stroke of the motor piston, and upon reversal of the motor piston the pawls hold the rifle bar against rotation, and as a result the spiral grooves thereof engaging the spiral lugs of the rifle nut cause the hammer piston to rotate as it moves rearwardly. Rotative movement of the hammer piston is transmitted to the drill steel through straight grooves 19 formed externally on the striking bar 4 and engaging straight lugs 20 formed internally on the chuck sleeve 8 which in turn carries the steel supporting chuck bushing. It will thus be seen that upon every retraction stroke of the hammer piston a slight rotative movement is imparted to the drill steel.

Now referring to the improved fluid distribution means and more particularly to the improved valve mechanism, it will be noted that formed within the rearward portion of the motor cylinder and in alignment with the piston chamber is an enlarged bore 21 which receives the ratchet ring 15, and interposed between the ratchet ring and a shoulder 22 formed on the cylinder are cooperating valve chest elements 23 and 24. The elements 23 and 24 are herein arranged in face to

55

face abutting relation and are clamped in position against the shoulder 22 by the head block 12 engaging the ratchet ring 15. In the present construction, formed in the valve chest element 5 23 and surrounding the rifle bar 17 is an annular valve chamber 25 having reciprocably mounted therein an annular flat disc or plate valve 26. This valve is provided with a central bore 27 and is slidably mounted upon and guided by the cylindrical portion of the rifle bar 17 in the manner shown. Formed on the valve chest elements 23 and 24 respectively at the opposite sides of the valve chamber are concentric annular seats 28, 29, 30 and 31, the seats 28, 29 arranged at the 10 opposite sides of an annular groove or recess 32 formed in the element 23, while the seats 30, 31 are arranged at the opposite sides of an annular groove or recess 33 formed in the element 24. Also arranged concentric with the grooves 32, 33 15 and formed in the valve chest elements 23, 24 respectively, are inner annular grooves or recesses 34 and 35. Also formed on the element 24 concentric with the grooves 33, 35 is an outer annular groove or recess 36. In the present construction the valve chamber is of slightly greater 20 diameter than the valve element 26 to provide a restricted annular passage past the valve through the valve chamber as clearly shown in Fig. 9. This particular valve design permits close regulation 25 of the flow of pressure fluid to the opposite ends of the piston chamber. The flow past the valve to the rear end of the piston chamber is regulated by the valve throwing space between the forward face of the valve and the front wall 30 of the valve chamber, while the flow to the front end of the piston chamber is regulated by the clearance space about the peripheral edge of the valve. The clearance space about the peripheral edge of the valve may obviously be more or less 35 than the throwing space between the forward face of the valve and the front wall of the valve chamber. Arranged transversely of the back head 12 is a throttle valve 37 having a central supply chamber 38 and radial passages 39 and 39a for 40 connecting the chamber 38 with a supply passage 40 formed in the back head and communicating with an annular chamber 41 surrounding an annular projection 42 integral with the back head and forming a bearing for the rear end of the rifle bar 17, as shown in Fig. 1. The chamber 41 45 communicates through the spaces formed between the ratchet teeth of the ratchet ring with an annular groove or recess 43 formed in the rearward face of the valve chest element 23. The recess 43 is connected by a series of longitudinal passages 44 formed in the valve chest element 23 with the annular groove 36. The central annular groove 33 formed in the rear face of the valve chest element 24 is communicable with the rear 50 end of the piston chamber through a series of longitudinal passages 45. The outer groove 32 formed in the valve chest element 23 at the rear side of the valve chamber is communicable with the front end of the piston chamber through a 55 pair of radial passages 46 formed in the element 23 and ports 47, longitudinal passages 48 and ports 49 formed in the motor cylinder. As above mentioned there are two sets of passages and ports 46, 47, 48, 49, but one set being shown in Fig. 8, while the two passages 48 are clearly shown in Fig. 6. Formed in the wall of the cylinder intermediate the ends thereof is an annular piston chamber exhaust groove 50 communicable through a lateral exhaust port 51 with the atmosphere. 60

Associated with the improved fluid distribution means above described is the improved hole blowing device. Formed in a lateral boss 52 integral with the cylinder is a longitudinal bore 53 herein arranged parallel with the piston chamber, while 5 also formed in the boss 52 parallel with the bore 53 is a bore 54. This latter bore forms a lubricant reservoir from which lubricant is supplied in an appropriate manner to the moving parts of the motor. Arranged in the bore 53 is a reciprocable plunger valve 55 having a sleeve-like body 56, and this valve when in the position shown in Fig. 5, cuts off communication between the exhaust groove 50 and the exhaust port 51. The plunger valve is actuated in the forward direction 10 and held closed by pressure fluid, and is returned to its inoperative or open position by a coiled spring 57 connected to a transverse pin 58 secured to the valve and to a pin 59 secured to a cylindrical plug 60 fitting within the rear end of the 15 bore 53. For supplying fluid to the bore 53 to actuate the valve 55 there is formed in the throttle valve 37 a radial passage 61 communicating with the pressure chamber 38 in the valve and a passage 62 formed in the back head 12. Communicating with the passage 62 is a passage 63 formed in the ratchet ring 15, and this passage in turn communicates with a radial passage 64 formed in the motor cylinder. The passage 64 is connected by longitudinal passage 65 and a radial 20 passage 66 communicating with the bore 53. Communicating with the grooves 35, 36 in the valve chest element 24 through ports 67, 68 respectively is a radial passage 69 in turn communicating through passages 70, 71, groove 12 (when 25 the valve 56 is in its foremost or closed position), and exhaust passage 73 communicating with the atmosphere. 30

The groove 35 is constantly supplied with live pressure through the ports 67 and 68 and the 40 passage 69 while the groove 34 is constantly supplied with live pressure through passages 74 formed in the valve chest element 23 as shown in Figs. 1 and 3, and communicating through the ratchet ring with the chamber 41. 45

In the operation of the improved fluid distribution means when the parts are in the position shown in Fig. 1 and the throttle valve 37 is turned to bring the passage 39 in communication with passage 40, pressure fluid may flow from the 50 pressure chamber 38 in the valve to the groove 41 and thence through the spaces between the ratchet teeth, groove 43, passages 44 to the annular groove 36. At this time the valve 26 is held against the annular seats 28, 29, cutting off 55 communication between the pressure chamber 36 and the longitudinal supply passages 40 communicating with the forward end of the piston chamber. Pressure fluid then flows from the chamber 36 through the valve chamber past the 60 forward face of the valve and through groove 33 and passages 45 to the rear end of the piston chamber, the pressure fluid acting on the rear face of the hammer piston to drive the latter forwardly to effect its working stroke, i. e. to 65 strike a blow on the shank of the drill steel. At this time the forward end of the piston chamber is open to exhaust through groove 50 and exhaust passage 51, and as the piston travels forwardly the groove 50 is cut off by the piston 70 head, and upon continued forward movement a substantial compression pressure is built up by the piston within the forward end of the piston chamber. As the rear edge of the piston head 75 overruns the exhaust groove 50, the rear end of

the piston chamber is connected to exhaust through exhaust passage 51, and as a result the pressure within the rear end of the piston chamber and in the groove 33 is substantially reduced. The compression pressure built up within the forward end of the pressure chamber, passages 48, 48 and groove 32 aided by the pressure fluid in the concentric groove 34 overcomes the opposed reduced pressure in the groove 33 and the pressure fluid in groove 35, thereby throwing the valve from the position shown in Fig. 1 to the position shown in Fig. 2. When the parts are in the position shown in Fig. 2, the valve is held against the concentric annular seats 30, 31, cutting off communication between the rear end of the cylinder bore and the annular supply groove 36, and pressure fluid then flows from the groove 36 through the valve chamber past the outer periphery of the valve, through groove 32, passages 46, ports 47 and passages 48 and ports 49 to the forward end of the piston chamber, the pressure fluid acting on the forward pressure area of the piston to drive the latter rearwardly to effect its retraction stroke. At this time the pressure at the forward end of the piston chamber is connected to exhaust through groove 50 and exhaust passage 51, and as the piston moves rearwardly the exhaust groove 50 is overrun by the piston, and upon continued rearward movement of the piston a substantial compression pressure is built up within the rear end of the piston chamber. As the piston moves rearwardly the forward edge of the piston head overruns the groove 50, connecting the forward end of the piston chamber to exhaust, and as a result the pressure within the forward end of the piston chamber and in passages 48, 49 and groove 32 at the rear side of the valve is substantially reduced. The compression pressure in the rear end of the piston chamber and groove 33 at the forward side of the valve aided by the pressure fluid in the groove 35 overruns the reduced pressure in the groove 32 and the pressure fluid in groove 34, and as a result the valve is thrown from the position shown in Fig. 1 to the initial position shown in Fig. 1, these operations being rapidly repeated during normal operation of the motor.

If it is desired to effect a hole blowing operation, that is, to supply a continuous flow of pressure fluid from the front end of the piston chamber through the rotation grooves 19 in the piston striking bar and thence through the chuck sleeve and the bore in the drill steel to the bottom of the drill hole, the operator rotates the throttle valve 37 to the position shown in Fig. 5 to bring the passage 39^a in communication with the passage 40 and passage 61 in communication with passage 62 so that without interrupting the flow of pressure fluid to the distribution means, pressure fluid is supplied from the chamber 38 through port 61, passages 62, 63, 64, 65, 66 to the bore 53 at the rear side of the valve 56, moving the latter forwardly from the position shown in Fig. 1 to the position shown in Fig. 5, thereby cutting off communication between the exhaust groove 50 and the exhaust passage 51. When the plunger valve 56 is in the position shown in Fig. 5, the groove 35 at the forward side of the valve is vented to atmosphere through passages 69 and 70, groove 72 in the valve and exhaust port 73, and the reduced pressure in the groove 35 at the forward side of the valve is overcome by the pressure in the groove 34, thereby causing the valve to assume the position shown in Figs. 2 and

5 with the pressure fluid flowing from the supply chamber through the supply passages to the forward end of the piston chamber. As a result of the cutting off of the cylinder exhaust and the venting of the forward side of the valve, the valve 5 is locked in the position shown in Fig. 2, and as a result, the pressure in the forward end of the piston chamber retracts the hammer piston and holds the same immovable in its rearmost position, as shown in Fig. 5. Pressure fluid then 10 flows continuously through passages 48, 48 to the front end of the piston chamber and thence through the grooves 19 in the piston striking bar and the chuck sleeve 8 and through the bore in the drill steel to the bottom of the drill hole to 15 blow the cuttings from the hole. When normal drilling is to be resumed, the throttle valve is turned into a position to vent the passage 62 to atmosphere in a suitable manner, and as a result, the plunger valve 56 is moved rearwardly into 20 its inoperative or open position by the coiled spring 51.

In the modified form of construction shown in Fig. 9, the operation of the fluid distribution means and exhaust control valve 56 is identical to 25 that above described with the exception that in this instance the vent port 69 communicating with the groove 35 is omitted, and when the plunger valve 56 is in the position shown, that is in the hole blowing position, the end of the piston 30 chamber is connected to atmosphere through passages 75, 76, the groove 72 and the vent port 73. It will thus be evident that when the exhaust control valve is in the position shown, the rear end of the piston chamber is vented to 35 atmosphere, and as the hammer piston moves rearwardly no compression pressure is built up within the rear end of the piston chamber to effect throwing of the valve in the rearward direction, and as a result the pressure in the valve chamber 40 at the rear side of the valve holds the valve immovable in its forward position. The hammer piston is then held retracted and the hole blown in the manner above described. Otherwise this form of the invention is identical to that above 45 described.

As a result of this invention, it will be noted that an improved pressure fluid motor is provided having an improved valve mechanism wherein the supply of pressure fluid to the piston chamber 50 is controlled in an improved manner resulting in a motor having more efficiency and a more rapid piston speed. It will further be noted that by associating with the improved fluid distribution means the improved hole blowing device, a hole 55 blowing operation is effected in an improved manner. These and other uses and advantages of the invention will be clearly apparent to those skilled in the art.

While there is in this application specifically described one form, and a modification thereof, which the invention may assume in practice, it will be understood that this form, and modification thereof, of the same is shown for purposes of illustration and that the invention may be 60 further modified and embodied in various other forms without departing from its spirit or the scope of the appended claims.

What I claim as new and desire to secure by Letters Patent is:

1. In a pressure fluid motor, a cylinder providing a piston chamber, a piston reciprocable in said chamber, and fluid distribution means for effecting reciprocation of said piston including a valve chest having a valve chamber, an annular disc 75

valve reciprocable in said valve chamber, a pair of concentric annular recesses formed in the valve chest at one side of the valve chamber, three concentric annular recesses formed in the valve chest at the opposite side of the valve chamber, annular seats surrounding certain of said annular recesses against which the opposite faces of the valve are adapted to seat, passage means connecting one of said pair of recesses with one end 10 of the piston chamber, passage means connecting one of said three recesses with the opposite end of the piston chamber, and passage means for supplying pressure fluid to all of said other recesses at the opposite sides of the valve chamber, said 15 fluid distribution means including means for conducting pressure fluid from one of said three concentric recesses to both of said recesses at the opposite sides of the valve chamber with which said first and second mentioned passage means 20 communicate.

2. In a pressure fluid motor, a cylinder providing a piston chamber, a piston reciprocable therein, and fluid distribution means for effecting reciprocation of said piston including a valve chest 25 arranged at the rear end of the cylinder and having a valve chamber, an annular disc valve reciprocable in said valve chamber, concentric annular grooves formed in the valve chest at opposite sides of the valve chamber, annular seats 30 surrounding said grooves against which the opposite faces of the valve are engageable, a series of longitudinal passages formed in the valve chest for connecting one of the grooves at the front side of the valve with the rear end of the piston chamber, passage means for connecting one of the 35 grooves at the opposite side of the valve with the opposite end of the piston chamber, a groove surrounding the grooves at one side of the valve chamber and communicating at its inner peripheral edge directly with the outer peripheral edge of said valve chamber, pressure fluid flowing from said groove under the control of the valve to said grooves with which said passage means communicate, and passage means for supplying pressure fluid to said last mentioned groove.

3. In a pressure fluid motor, a cylinder providing a piston chamber, a piston reciprocable therein, and fluid distribution means for effecting reciprocation of said piston including a valve chest 50 arranged at the rear end of the cylinder and having a valve chamber, an annular disc valve reciprocable in said valve chamber, concentric annular grooves formed in the valve chest at opposite sides of the valve chamber, annular seats 55 surrounding said grooves against which the opposite faces of the valve are engageable, a series of longitudinal passages formed in the valve chest for connecting one of the grooves at the front side of the valve with the rear end of the piston chamber, passage means for connecting one of the 60 grooves at the opposite side of the valve with the opposite end of the piston chamber, a fluid supply groove surrounding said concentric grooves at one side of said valve chamber and communicating with the opposite sides of said valve chamber for supplying pressure fluid to the latter, a second fluid supply groove formed in the rear face of the valve chest, and a series of longitudinal 65 passages formed in the valve chest for conducting pressure fluid from said second fluid supply groove to said first fluid supply groove.

4. In a pressure fluid motor, a cylinder providing a piston chamber, a piston reciprocable therein, and fluid distribution means for effecting reciprocation of said piston including a valve 70

chest arranged at the rear end of the cylinder and having a valve chamber, an annular disc valve reciprocable in said valve chamber, a pair of concentric annular grooves formed in the valve chest at the rear side of the valve chamber, three 5 concentric annular grooves formed in the valve chest at the front side of the valve chamber, annular seats surrounding certain of said grooves against which the opposite faces of the valve are engageable, passage means for supplying pressure fluid to the inner of said grooves, passage 10 means for connecting said outer groove of said pair and the central groove of said three with the opposite ends of the piston chamber, and passage means for supplying pressure fluid to 15 the outer of said three grooves.

5. In a pressure fluid motor, a cylinder providing a piston chamber, a piston reciprocable therein, and fluid distribution means for effecting reciprocation of said piston including a valve 20 chest arranged at the rear end of the cylinder and having a valve chamber, an annular disc valve reciprocable in said valve chamber, a pair of concentric annular grooves formed in the valve chest at the rear side of the valve chamber, three 25 concentric annular grooves formed in the valve chest at the front side of the valve chamber, the outer of said three concentric grooves communicating with the opposite sides of said valve chamber for supplying pressure fluid to the latter, annular seats surrounding certain of said grooves against which the opposite faces of the valve are engageable, passage means for supplying pressure fluid to the inner of said grooves to provide a constant valve throwing pressure acting 30 on the opposite faces of said valve, passage means for connecting said outer groove of said pair and the central groove of said three with the opposite ends of the piston chamber, and passage means for supplying pressure fluid to the outer 35 of said three grooves, pressure fluid flowing from the outer of said three grooves under the control of the valve to the outer of said pair of grooves and to the central groove of said three grooves.

6. In a pressure fluid motor, a cylinder providing a piston chamber, a piston reciprocable in said piston chamber, and fluid distribution means for effecting reciprocation of said piston including a valve chest having a valve chamber of uniform bore, an annular, flat disc valve reciprocable in said chamber, means for guiding said valve at its inner peripheral edge, there being provided a restricted clearance about the outer peripheral edge of the valve between the valve and the valve chamber, and means for actuating said valve and conducting fluid to effect piston actuation including means forming a passage leading from one end of said valve chamber to one end of the piston chamber, means forming a passage leading from the opposite end of said valve chamber to the opposite end of the piston chamber, and means for conducting piston actuating fluid to said valve chamber having communication with the latter at a point such that all the fluid flowing from said conducting means to the passage of one of said passage forming means must pass through said restricted clearance and then radially of one end of said valve while fluid passing from said conducting means to the passage of the other of said passage forming means passes across the opposite end surface of said valve thereto.

7. In a pressure fluid motor, a cylinder providing a piston chamber, a piston reciprocable in 75

said piston chamber, and fluid distribution means for effecting reciprocation of said piston including a valve chest having a valve chamber of uniform bore, an annular, flat disc valve reciprocable in said chamber, means for guiding said valve at its inner peripheral edge, there being provided a restricted clearance about the outer peripheral edge of the valve between the valve and the valve chamber, and means for actuating said valve and distributing fluid under its control, to effect piston actuation, including means forming a passage leading from one end of said valve chamber to one end of the piston chamber, means forming a passage leading from the opposite end of said valve chamber to the opposite end of the piston chamber, and means for conducting piston actuating fluid to said valve chamber having communication with the latter at a point such that all the fluid flowing from said conducting means to the passage of one of said passage forming means must pass through said restricted clearance and then radially of one end of said valve while fluid passing from said conducting means to the passage of the other of said passage forming means passes across the opposite end surface of said valve thereto, the area of the space about the peripheral edge of said valve being different from the valve chamber area through which pressure fluid flows past one end surface of the valve thereby to provide regulation for flow of the pressure fluid flowing to the opposite ends of said piston chamber.

8. In a pressure fluid motor, a cylinder providing a piston chamber, a piston reciprocable in said piston chamber, and fluid distribution means for effecting reciprocation of said piston including a valve chest having a valve chamber of uniform bore, concentric annular grooves formed in each end wall of said valve chamber and having annular seats surrounding the same, an annular, flat disc valve reciprocable in said valve chamber and engageable with said seats, said valve being of less diameter than said valve chamber to provide a restricted clearance about the peripheral edge of said valve, means forming a passage leading from one groove at one end of said valve chamber to one end of the piston chamber, and means forming a passage leading from a groove at the other end of said valve chamber to the opposite end of said piston chamber, means for supplying fluid to the others of said grooves, and means for conducting piston actuating fluid to said valve chamber having communication with the latter at a point such that all the fluid flowing from said conducting means to the passage of one of said passage forming means must pass through said restricted clearance, then radially of one end of said valve and through the groove communicating with the passage, while fluid passing from said conducting means to the passage of the other of said passage forming means passes across the opposite end surface of said valve and through the other groove to the passage.

65 9. In a pressure fluid motor, a cylinder providing a piston chamber, a piston reciprocable in said piston chamber, and fluid distribution means for effecting reciprocation of said piston including a valve chest having a valve chamber of uniform bore, concentric annular grooves formed in each end wall of said valve chamber and surrounded by annular seats, an annular, flat disc valve reciprocable in said valve chamber and engageable with said valve seats, said valve being of less diameter than said valve

chamber to provide a restricted clearance about the peripheral edge of said valve, means forming a passage leading from one of the grooves at one end of the valve chamber to one end of said piston chamber, means forming a passage leading from one of said grooves at the opposite end of the valve chamber to the opposite end of the piston chamber, means for supplying pressure fluid constantly to the others of said concentric grooves, and means for conducting piston actuating fluid to said valve chamber having communication with the latter at a point such that all the fluid flowing from said conducting means to the passage of one of said passage forming means must pass through said restricted clearance, then radially of one end of said valve and through the groove to the passage, while fluid passing from said conducting means to the passage of the other of said passage forming means passes across the opposite end surface of the valve through the groove to the passage, said valve being thrown into its opposite positions by the constant pressure in said other concentric grooves and by compression pressure built up by the piston within the opposite ends of the piston chamber and in said supply passages.

10. In a pressure fluid motor, a cylinder providing a piston chamber, a piston reciprocable therein, and fluid distribution means for effecting reciprocation of said piston including a valve chest comprising cooperating plates, a circular recess formed in the face of one of said plates, said other plate having its adjacent face abutting said face of said other plate to form the outer wall of said recess, a flat disc valve reciprocable in said recess, the adjacent faces of said plates at the opposite ends of the valve chamber each having formed therein concentric annular grooves struck on the same radii from a common center, a third groove formed in the adjacent face of one of said plates, means for supplying pressure fluid to said third groove, means forming a motive fluid supply passage communicating with one of the concentric grooves on one of said plates and with one end of the piston chamber, means forming a motive fluid supply passage communicating with one of the concentric grooves on the other plate and with the opposite end of the piston chamber, and means for supplying pressure fluid constantly to the others of said concentric grooves, said valve being thrown by said constant pressure and compression pressure built up in said supply passages by said piston and in its different positions controlling pressure fluid flow through said supply passages to said piston chamber.

11. In a pressure fluid motor, a cylinder providing a piston chamber, a piston reciprocable therein, and fluid distribution means for effecting reciprocation of said piston including a valve chest comprising cooperating abutting plates, the front face of the rear plate being circularly recessed and the rear face of the front plate forming a closure for said recess, a flat disc valve reciprocable in said recess and of a diameter less than the diameter of said recess to form a clearance about the peripheral edge of said valve, concentric grooves formed in the face of each plate and communicating with the opposite ends of said recess at the opposite sides of said valve, said concentric grooves formed on radii of the same length struck from a common center, a third annular groove formed in the rear face of said front plate on radii of greater length

than said concentric grooves but struck from the same center, said third groove communicating near its inner periphery with the exterior periphery of said recess, means forming a passage connecting one of the concentric grooves in the front plate with the rear end of the piston chamber, means forming a passage connecting one of the concentric grooves of the rear plate with the forward end of the piston chamber, and means forming passages for supplying pressure fluid constantly to the others of said concentric grooves, said valve being thrown by the constant pressure in said other concentric grooves and compression pressure built up by the piston

in said supply passages, said valve when in one position permitting fluid flow from said third groove through the valve chamber past the forward face of the valve through the communicating concentric groove and supply passage to the rear end of the piston chamber and when in its opposite position permitting fluid flow from said third groove through the clearance about the peripheral edge of the valve through the other communicating concentric groove and supply passage to the forward end of the piston chamber. 5 10

MERVIN CHESTER HUFFMAN.
